Dec. 789

Anthony J. Gallagher, of Philadelphia, Pa.
Letters Patent, No. 789, Dated May 13th 1836.

The schedule referred to in these Letters Patent, and making part
of the same.

To all whom it may concern: Be it known that I,

Anthony J. Gallagher, of the City of Philadelphia, in the County of Philadelphia, and State of Pennsylvania, have invented or produced a new and original design for a cooking stove, which he has named the "Sunrise airtight". And I do hereby declare that the following is a full and exact description of the same, reference being made to the accompanying drawings, which form part of this specification.

Fig 1. Is a section of the top of the stove, with the ornaments, viz, raised ^{dots} and diamond shaped figures.

Fig. 2. Is the side fire door, with the ornaments, - big- raised figures in the form of stars, dots and diamonds.

Fig 3 & 4. Are the two oven doors with the ornaments, - big- raised figures in the form of stars, dots and diamonds.

all the ornaments, or figures, are raised above the surface of the plates upon which they are placed.

What I wish to claim and secure by Letters Patent, is the arrangement and combination of the ornaments that form the design herein above specified.
